DESIGN FOR A RIPPING DEVICE

Blanche L. Chatfield, Washington, D. C.

Application November 28, 1939, Serial No. 88,534

Term of patent 14 years

To all whom it may concern:

Be it known that I, Blanche L. Chatfield, a citizen of the United States, residing at Washington, District of Columbia, have invented a new, original, and ornamental Design for a Ripping Device, of which the following is a specification, reference being had to the accompanying drawing, forming part thereof.

In the drawing, Figure 1 is a perspective view of a ripping device showing my new design and Figure 2 is a bottom plan view of the device shown in Figure 1.

I claim:

The ornamental design for a ripping device, substantially as shown.

BLANCHE L. CHATFIELD.
